FOLDING CASE

Filed May 18, 1922

2 Sheets-Sheet 2

UNITED STATES PATENT OFFICE.

JOSEPH W. O. ORBAN, OF BROOKLYN, NEW YORK.

FOLDING CASE.

Application filed May 18, 1922. Serial No. 561,908.

To all whom it may concern:

Be it known that I, JOSEPH W. O. ORBAN, a citizen of the United States, and a resident of the city of New York, borough of Brooklyn, in the county of Kings and State of New York, have invented a new and Improved Folding Case, of which the following is a full, clear, and exact description.

This invention has relation to folding cases, crates, or coops which are designed for the purpose of shipping animals, poultry or articles of merchandise, when in set-up condition, and which are designed to be collapsed when empty for the purpose of re-shipment whereby the same will occupy a minimum amount of space.

One of the principal objects of the present invention resides in the provision of a folding case or crate in which all of the elements thereof are permanently connected together in order to prevent loss thereof.

As a further object the invention contemplates in a folding case or crate a plurality of permanently connected elements which coact with one another when the same is set-up to retain the same in its set-up condition and to strengthen and brace the structure.

As a further object the invention contemplates a folding or collapsible case or crate in which the elements are so associated as to permit of the folding and nesting thereof into a compact article which substantially reduces the amount of space required for its storage or shipment, and which affords complete protection for the elements against breakage or other damage when empty.

The invention furthermore contemplates a folding case or coop which is comparatively simple in its construction, inexpensive to manufacture and produce, and which may be readily collapsed or set up.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

55

Figure 1 is a perspective view of a crate or coop constructed in accordance with the invention, illustrating the same in its set up condition.

Fig. 2 is a horizontal sectional view taken approximately on the line 2—2 of Fig. 1.

Fig. 3 is a transverse sectional view taken approximately on the line 3—3 of Fig. 2.

Fig. 4 is a perspective view of the same in collapsed or folded condition.

65

Fig. 5 is a horizontal sectional view therethrough taken approximately on the line 5—5 of Fig. 4.

Fig. 6 is a transverse sectional view therethrough taken approximately on the line 6—6 of Fig. 5.

70

Fig. 7 is an enlarged detail fragmentary sectional view taken approximately on the line 7—7 of Fig. 4.

75

Fig. 8 is a fragmentary detail sectional view taken approximately on the line 8—8 of Fig. 2.

Referring to the drawings by characters of reference, the case or crate embodies front and rear walls 10 and 11, the former being provided with rearwardly projecting end flanges or cleats 12 and the latter with forwardly projecting end flanges or cleats 13. The front and rear walls are connected for relative movement toward and away from each other through the medium of foldable end walls 14, each of which comprise a pair of leaf sections 15 having hinged connection with each other at their inner ends by means of hinges 16 and having hinged connection at their outer ends respectively with the flanges or cleats 12 and 13 of the front and rear walls by means of hinges 17. Under this arrangement when the leaf sections 15 are swung inwardly to bring their outer faces in parallel relation, the inner faces thereof are disposed in parallel relation with the inner sides of the front and rear walls whereby said front and rear walls are advanced toward each other. A bottom wall 18 is hingedly connected at its forward edge by hinges 19 with the lower portion of the front wall 12 at the inner side thereof. The front and rear walls are provided with longitudinally extending rabbeted strips 20 and 21 at their inner lower edges which are designed to receive in their rabbeted portions the front and rear edges of the bottom wall

18 when the crate is in set-up condition. The hinges 19 serve to permit of the swinging of the bottom wall 18 to dispose its upper face in parallel relation to the rear or 5 inner face of the front wall upon collapsing or folding of the case. A cover or top 22 is hingedly connected at its rear end to the upper edge of the rear wall 11 by means of hinges 23 and the forward free edge thereof 10 is rabbeted as at 24 on its under side to coact with the complementary rabbeted upper and inner edge 25 of the front wall 10. A vertical partition 26 for dividing the case 15 compartments is hingedly connected at its rear edge to the medial portion of the rear wall 11 by means of hinges 27. The front wall is provided with a medial vertical cleat or strip 28 with which the forward free edge 20 of the partition 26 is adapted to coact to constitute a limiting stop therefor. The hinges 27 permit of the swinging movement of the partition 26 to dispose one of its sides parallel to the inner side of the rear wall 25 11 when collapsing or folding the crate. The front wall 10 is provided with longitudinally or transversely spaced doorways or 30 openings 20 which are designed to constitute independent entrance or exit passages to the compartments defined by the partition 26. A door 30 is provided with each doorway 29 and the same are hinged to the front wall by means of the hinges 31 to permit of the swinging of the same to open 35 or closed position with respect to said doorways. Suitable latch elements 32 are provided on each door 30 and are designed to coact with keepers 33 for securing the doors in closed position. The inner face of one of 40 the doorways is recessed as at 34 and has provided therein a keeper element or staple 35 with which the catch or hook 36 carried by the free forward end of the partition 26 is designed to coact for holding the partition 45 against casual or accidental closing when the case is set up. The forward end of the cover or top 22 is provided with a latch or hook 37 which is designed to engage and coact with a keeper or eye 38 carried by 50 the upper end of the front wall 10 to lock and retain the cover in closed condition. The bottom 18 is provided at its upper rear edge with a handle or ring 39 to afford convenient means for swinging said bottom upwardly on its hinges in collapsing the crate. 55 Assuming the crate or case to be in a set-up condition the folding or collapsing of the same is accomplished in the following manner. After the latch or hook 37 is disengaged from the keeper or eye 38, the top or cover 22 is swung upwardly and rearwardly and then downwardly to dispose the same in rear and parallel to the rear wall 11. The latch or hook 36 of the partition 26 is 60 then disengaged from the keeper or staple 65

35 and the partition 26 is then swung laterally and rearwardly into parallel relation with the inner side of the rear wall. The manipulating element or ring 39 is then grasped and the bottom wall is swung upwardly and forwardly into parallel relation with the front wall 10. The leaf sections 15 of the end walls 14 are then folded inwardly to advance the front and rear walls 10 and 11 toward each other and to dispose the leaf sections in parallel relation to each other and to the front and rear walls. 75

In order to lock and retain the case or 80 crate in the folded condition set forth, latch elements or hooks 40 are employed which are connected as at 41 to the cleats or flanges 13 of the rear wall. The free ends of the latch elements or hooks 40 are designed to engage in keepers or eyes 42 provided on the cleats or flanges 12 of the front wall. To retain the top or cover 22 in folded condition, a keeper element 43 is employed which preferably consists of a latch rod 44 mounted for sliding and turning movement in a recess 45 in one of the end flanges or cleats 13 of the rear wall. The latch rod extends through an apertured cover plate 46 for the recess 45 and the inner end thereof is provided with a pin or head 47 between which and said cover plate a coiled contractile spring 48 is interposed. The free outer end of the latch rod is provided with a right angularly bent terminal 49 which is designed to be turned laterally and engaged over the side edge of the cover or top 22. Preferably said cover or top 22 is grooved or notched as at 50 to receive and embrace the terminal 49 to prevent displacement thereof. The spring 48 functions to frictionally maintain the terminal 49 against the top or cover 22 and hold the same within the notch or groove 50. When not in use the latch rod is pulled outwardly to disengage the terminal 49 from the notch or groove 50 and is turned laterally whereby the spring will function to draw the terminal 49 into engagement with the rear face of the flange or cleat 30. 100

Assuming the case or crate to be in collapsed or folded condition, as illustrated in Fig. 4, the setting up thereof is accomplished in the following manner: The latch elements or hooks 40 are disengaged from the keepers or eyes 42 and the front and rear walls are relatively separated to effect the swinging of the leaf sections 15 of the end walls outwardly until said sections are in alignment. The bottom wall is then swung downwardly on its hinges 19 until the lower face at its front and rear edges are received and engaged within the rabbeted strips 20 and 21. The partition 26 is then swung forwardly and laterally until its free forward edge engages the cleat 28. This disposes the partition transversely across the 115 120 125 130

bottom wall 18 whereby the lower edge of said partition will lock and retain said bottom wall 18 within the rabbeted strips 20 and 21. The latch or hook 36 is then engaged in the staple or keeper 35. The keeper 43 is then disengaged from the top or cover 22 and said top or cover is swung upwardly, forwardly and downwardly until the rabbeted forward edge 24 lies within 10 the complementary rabbeted upper edge of the front wall. The latch or hook 37 is then engaged in the keeper or eye 38.

In its set up condition it will be observed that access may be independently obtained 15 to either compartment defined by the partition 26 by releasing the latches 32 from the keepers 33 whereby the doors may be swung to open position with respect to the doorways.

20 I claim:

1. A folding or collapsible container embodying side walls having inwardly projecting rabbeted cleats at their inner and lower edges, inwardly foldable end walls 25 consisting of a pair of sections hinged respectively to said sides at the opposite ends thereof and hinged to each other in parallel relation with the first mentioned hinged connection, a downwardly foldable 30 bottom wall having hinged connection to one of the side walls within the same and adapted to be received within the rabbeted cleats for holding the side walls in relatively spaced relation and the end wall sections 35 in alignment and against inward folding, a partition hingedly connected at one side with the inner portion of one of the side walls and adapted to be swung to a position transversely of the container with 40 its free edge in abutting relation with the inner side of the opposite side wall and interengageable means carried by the free edge of said partition and the opposite side wall with which it engages for retaining 45 the partition against movement, said partition constituting an auxiliary means for holding the side walls in separated relation and for retaining the bottom wall within the rabbeted cleats.
2. A folding or collapsible container comprising a pair of side walls, a pair of end walls including inwardly foldable sections having a hinged connection with each other at their inner edges and having hinged connection 50 at their outer edges respectively with the ends of the opposite side walls, a bottom wall having hinged connection at one side edge to the lower inner side edge of one of the side walls and engageable 55 within the lower side edge of the opposite wall, said bottom wall adapted to fold upwardly in parallel relation with the side wall to which it is hinged, a transverse partition having hinged connection with one of the side walls and engageable at its free edge with the opposite side wall to normally 60 overlie the bottom wall for holding the same against upward folding, said partition being foldable against the side wall with which it is hinged in parallel relation thereto upon collapsing of the container, a top wall having hinged connection at one of its side edges with the upper side edge of one of the side walls and adapted when the container is set up to lie within the upper edges 65 of the opposite side wall and the end walls, said top adapted to be swung upwardly, rearwardly and downwardly to lie in rear of and parallel to the side wall with which it is hingedly connected, and interengageable means carried by the side walls 70 adapted upon engagement with each other to hold the container in collapsed condition.
3. A folding or collapsible container comprising a pair of side walls, a pair of end walls including inwardly foldable sections having a hinged connection with each other at their inner edges and having hinged connection 75 at their outer edges respectively with the ends of the opposite side walls, a bottom wall having hinged connection at one side edge to the lower inner side edge of one of the side walls and engageable within the lower side edge of the opposite wall, said bottom wall adapted to fold upwardly 80 in parallel relation with the side wall to which it is hinged, a transverse partition having hinged connection with one of the side walls and engageable at its free edge with the opposite side wall to normally overlie the bottom wall for holding the same against upward folding, said partition being foldable against the side wall with which it is hinged in parallel relation thereto upon collapsing of the container, a top wall having hinged connection at one of its side edges with the upper side edge of one of the side walls and adapted when the container is set up to lie within the upper edges 85 of the opposite side wall and the end walls, said top adapted to be swung upwardly, rearwardly and downwardly to lie in rear of and parallel to the side wall with which it is hingedly connected, and interengageable means carried by the side walls 90 adapted upon engagement with each other to hold the container in collapsed condition.

JOSEPH W. O. ORBAN.
